Patented Aug. 26, 1919.

UNITED STATES PATENT OFFICE.

ARTHUR L. RUSSELL, OF BOSTON, AND CHARLES E. GRUSH, OF BEVERLY, MASSACHUSETTS, ASSIGNORS, BY MESNE ASSIGNMENTS, TO UNITED SHOE MACHINERY CORPORATION, OF PATERSON, NEW JERSEY, A CORPORATION OF NEW JERSEY.

STRETCHING-MACHINE.

1,313,917.

Specification of Letters Patent. Patented Aug. 26, 1919.

Application filed March 27, 1914. Serial No. 827,609.

To all whom it may concern:

Be it known that we, ARTHUR L. RUSSELL and CHARLES E. GRUSH, citizens of the United States, residing at Boston, in the 5 county of Suffolk and State of Massachusetts, and at Beverly, in the county of Essex and State of Massachusetts, respectively, have invented certain Improvements in Stretching-Machines, of which the following description, in connection with the accompanying drawings is a specification, like reference characters on the drawings indicating like parts in the several figures.

This invention relates to the manufacture 15 of articles which are generally to conform to surfaces over which they are to be placed and has for its objects to provide a machine by which an economy of material can be effected, labor costs reduced and the fit of 20 articles improved and made more permanent.

The invention is embodied in a machine by which may be effected local stretching of 25 interior portions of stock progressively as by repeated operations of the machine upon the same, adjacent, or successive portions of the stock. Advantageously a small width only 30 of stock will be subjected to tension at a time and then relieved, and the same or an adjacent portion of the stock subjected to tension at the next operation of a continuously running machine. Thus by 35 repeated action of the machine, interior portions of an upper may be permanently stretched before application to a last to fit the curved faces of the last and the low and the high or prominent portions of the last, as for example the high toes, the low balls and the deep shanks of modern lasts. Advantageously the machine is organized to 40 seize a portion of stock at adjacent points or on adjacent lines and, by movement of the engaging means relatively apart, to stretch the intervening portion of the stock in the 45 direction relatively to the length of the last which is required to make the upper fit over the particular portion of the last upon which it is to be applied. The machine, or it may be the operator, will then transfer 50 the stock in the direction of feed, release the stock, move reversely to the direction of feed, and into relation for again similarly seizing an adjacent portion of the stock, the

stock being turned if desired while it is released to obtain the desired directions for 55 successive stretching movements. Provisions may be made for varying the length and also the direction of the pulling and also the feeding movements, with opportunity for the operator to accelerate or diminish the feed if desired, so that the extent of stretching, the closeness of stretched portions together, including it may be, overlapping thereof or spacings therebetween, as well as repetition of the stretching action 60 back and forth across the stock may be obtained at the will of the operator, the stock supporting means being adapted to facilitate turning of the stock by the operator to facilitate stretching in directions inclined to 65 one another, in the preferred embodiment of the invention.

In the machine selected for illustration, a work table serves to support the stock, and two pincers, which are supported for movements in opposite directions to stretch and feed the stock, have their gripping jaws located near the middle of the table. The lower jaw of each of these pincers is rigid 75 with its carrier arm and projects up through a slot in the table and supports the interior portion of the stock which is being stretched, while each coöperating upper jaw is movably sustained from its respective pincer arm for stock seizing and releasing action, by a plurality of parallel, outwardly inclined links, the links for one movable jaw being inclined oppositely from those of the other movable jaw. These pincers are so actuated as to alternately move toward and 80 from each other to stretch and feed the stock. An extended arm from one of the links of each movable jaw may be provided which will have sliding engagement with a 85 rod carrying yielding means for coöperating with a crank arm which may be shifted to one side or the other from a central position by manually-operable devices, including a knee fork to control the length and direction of the feeding movements which will be imparted to the stock by the pincers for securing the desired extent of stretching, and the closeness of the stretched portions to each other. When the crank arm is permitted to 90 remain in a neutral position the machine 95 will impart repeated stretching movements 100 105

to the same portion of the stock or will permit the operator to manipulate the stock to feed it as desired.

The various features of the invention, 5 many of which are believed to be broadly novel, including certain highly desirable combinations of parts and more important details of construction, will be described in connection with the accompanying drawings 10 and will then be pointed out in the claims.

In the drawings:—

Figure 1 is a perspective view, partly sectional, of an illustrative machine embodying the invention; and

15 Fig. 2 is a detail view in front elevation, on a reduced scale, of certain parts illustrated in Fig. 1.

The machine frame is provided with a base 3 having holes 4 to receive bolts for 20 clamping to a suitable support. The frame also sustains bearings for a driving shaft 6 to which is secured a pulley 8 for receiving power through a belt from any convenient 25 source. A work table 10 is sustained from the frame and has a slot or opening 12 located interiorly of its edges and preferably near its middle.

The pincers comprise upper jaw carrying arms 20, 24 respectively, extending over the 30 table 10 and lower jaw carrying arms 22, 26 extending under the table, each lower arm having a foot 65 confined and guided in the frame by plates 66 for movement lengthwise of the arms toward and from the opening 12 in the table. The lower arms 22, 26 carry vertically fixed jaws 28, 30 which project upwardly through the opening 12 in the table 10 and hold the work raised slightly above the face of the table. The upper arms 40 20, 24 carry respectively coöperating jaws 32, 34 each of which is suspended from its arm by a pair of parallel links 36, 37 and 38, 39, Fig. 1. The links are inclined outwardly so that as the pincers are moved 45 apart, Fig. 2, one toward the left and the other toward the right, they will be caused by the pull of the stock to grip and hold with increasing force.

The initial grip of the stock is produced 50 by the closing springs 49, guided on rod 44 and acting against the upward extensions 40, 41 of one link 36, 39 of each pincer. These extensions constitute levers arranged so that they can be pressed together between the 55 thumb and forefinger of one hand to raise the two upper jaws 32, 34 simultaneously for insertion of the work.

The rod 44 passes loosely through the lever extensions 40, 41 at 42, 43 and on its 60 oppositely threaded end portions the rod carries adjustable abutments 45, 45 against which the lever extensions strike near the outer ends of the pincers pulling movements. By this engagement with the stops 65 45 the links 36, 37 and 38, 39 are turned in

the direction to lift the jaws 32, 34 and release their grip on the work.

The points in their stroke at which this release occurs, and therefore the length of the upper pulling or stretching movements, 70 is determined by the positions of the stops 45 and this can be adjusted by turning the rod which for this purpose has a rigid collar 47 with radial holes for application of an instrument by which to rotate the rod. The 75 stops 45 are prevented from turning by square heads that have a sliding fit between side plates of the arms 20, 24.

During the return movement of the pincers, toward each other, to starting position 80 the inclination of the links enables the jaws 32, 34 to slide easily over the work. The operator usually keeps his hands upon the work to hold it smoothly outspread and to guide it so that the stretching pulls shall be 85 in the desired directions lengthwise, transversely or obliquely of the piece of work being shaped.

The pincers may be caused to feed the work automatically toward the right or 90 toward the left as an incident to their upper stretching operation. As herein shown this is accomplished by releasing one pincer from the upper during the pulling movement while the other continues its outward movement with its jaws gripped upon the work and thereby moves the work in the direction toward which it is traveling. In the illustrative machine the rod 44 carrying the stops is adjusted endwise, freely through levers 95 40, 41, to locate one or the other stop farther from the gripping point according to the direction of feed desired.

The rod 44 has a fixed collar 46 between which and the collar 47 the rod is embraced 105 by an arm 48 of a rock-shaft 50 mounted in a bearing arm 100 of the frame. At its rear end rock-shaft 50 has an arm 52 having the lost motion provided between the stops *a* *c* on the arm and the stop *b* rigid with the rock-shaft. The free end of arm 52 is connected at 55 by rod 54 with angle lever 56 on which is a knee fork 58 through which the operator can rock the shaft 50 to place one stop 45 nearer than the other to its lever 110 40 or 41. In such position the nearer stop 45 will cause its coöperating lever to lift its jaw 32 or 34 while the other jaw continues to hold the upper. The pincer so holding on to the upper will therefore feed the upper in 115 the direction of its movement at the end of each stretching movement of the pincers and therefore will present a fresh portion of stock to be gripped and stretched at each operation of the machine. The direction of feed is determined by the direction of movement of knee fork 58. The length of feed is determined by the extent of movement of the knee fork. The lost motion at *a*, *b*, *c* prevents undesired feeding when manual 120 125 130

manipulation of the work by the operator's hands is preferred. Springs 60, 60 above and below guide 57 center the knee fork normally. A spring plunger 63 having a 5 tapering head located in a V-shaped notch in arm 48 normally centers the rock-shaft. Adjustment of the arm 48 toward one or the other of the springs 49 will vary the force with which said spring presses the movable 10 jaw, associated with it, toward the fixed jaw.

The reciprocatory movements of the pincers, by which the jaws are carried into gripping position, then moved reversely to stretch the upper until released by the 15 stops 45 and are then returned, are effected through link connections 67, Fig. 2, between the lower arms 22, 26 of the pincer and a reciprocated bar 68. The bar is operated by a crank pin 72 of a crank disk on the front 20 end of the shaft 6. Preferably the bar has a cam slot 70 in which the crank pin works to accelerate the movement of the pincer during the first portion of the throw of the crank and to retard it before the return 25 stroke begins, the object being to obtain a quick grip and initial stretch with a slow final stretch amounting nearly to a dwell.

The design of the cam slot 70 is shown as such that when the crank pin starts downwardly, Fig. 2, for example toward the left, and the pincers grip and begin to pull the upper, the crank pin encounters the upwardly inclined lower face of the left hand portion of slot 70. It therefore moves bar 30 68 downwardly, and the pincers apart, at a rate determined by its own downward movement plus the upward inclination of the slot. During the second 90° of its throw the crank pin moves backwardly down the cam 35 slot toward its middle and therefore the bar 68 and the pincers are slowly moved during the second quarter of the crank throw a distance equal to the difference between the length of the crank throw and the length of 40 the cam incline. In practice differently shaped cams are appropriate for different classes of work. The machine may run continuously or may be equipped with a treadle controlled clutch, not shown.

45 In the use of the machine, the operator first presses inwardly upon the handled extensions 40, 41, compressing the springs 49, and causing the upper jaws of the pincers to be lifted by the parallel links. The shoe 50 upper or other sheet of stock to be operated upon is then placed on the work table, the clearance between the upper and lower arms of the pincers, as well as between the upper and lower jaws, permitting the work to be 55 positioned so that any desired interior portion of the work remote from its edges may be inserted between the jaws of the pincers. The handles 40 and 41 are then released and the springs 49 will cause the upper jaws 60 to clamp the work against the lower jaws of 65 the pincers with a light, yielding pressure. The reciprocation of the bar 68 will thus effect, through the links 67, simultaneous inward and outward movements of the pincers. The work is manually held smooth and 70 in slight frictional contact with the table and at each outward movement of the pincers the stock which has been seized by the jaws thereof will be stretched until the lever extensions 40, 41, or either of them strike 75 the release stops 45 after which if one release stop is struck first the stock will be fed toward the other one by the continued pull of the pincer associated with said other stop. Since the dimensions and relations of 80 the pairs of jaws are such that the extent through which they grasp the stock in the direction of stretching movement is considerably greater than the normal or initial separation between the adjacent edges of 85 the pairs, the stretching action is more sharply localized and under closer control by the operator than would be the case were the jaws narrow and allowed the action to extend back of the engaging surfaces. Upon 90 a reverse or inward movement of the pincers the movable jaws 32, 34 will, by reason of the inclined position of their supporting links, slide over the stock, which latter will be reengaged by the jaws and further 95 stretched when the pincers again move outwardly. The direction in which the operator shifts the knee lever and consequently the release stops 45 controls the direction in which the stock will be fed, and the amount 100 of such shifting movement controls the length of the feed as well as the length of the pulling movement.

105 It will be seen that with this machine the operator can stretch different portions of the leather which is to be used for shoe uppers, and especially those parts which are designed to fit over the high portions of the curved contour of a last, as for example, the high toe, and that the amount of stretching 110 which the leather receives, as well as its location, may be readily controlled by the operator. The upper may not only be stretched along parallel lines back and forth by controlling the direction of feed but during 115 the intervals between pulling movements of the pincers the operator may turn the work so as to obtain successive stretching effects in all desired directions. This is important in shaping a vamp to a high-toed 120 last because the best results are obtained by stretching from the center or highest point outwardly in all directions. In shaping the upper to fit the last back of the high toe to prevent bridging from the toe to the instep 125 stretching in a direction lengthwise of the last only is required to provide the fullness to lay down in that hollow portion of the last; similarly in shaping the shank portions of a shoe upper to fit into a narrow 130

shank last the direction of stretching will be chiefly lengthwise and will range from a maximum at and near the edge to a minimum remote from the edge. This gradation 5 of the stretching action may be obtained by varying the rate of feed, increasing the rate of course as the operation progresses away from the edge. In forming the heel pocket to fit around the ball of the heel the 10 stretching may be largely or entirely lengthwise to produce the necessary fullness for this purpose with the desired close fit around the edge of the heel seat.

Having explained the nature of this invention and described an illustrative machine embodying the same in the best form now known to us, we claim as new and desire to secure by Letters Patent of the 15 United States:—

1. A machine of the class described having, in combination, means for supporting stock, and continuously operating means constructed and arranged to grip a sheet of leather over two small areas located wholly 20 within and remote from the edges of the sheet and while maintaining a fixed engagement with the sheet to move apart in a plane parallel with the surface of the sheet for applying local stretching to an interior 25 portion of the stock by repeated operations 30 of the machine.

2. A machine of the class described having, in combination, means for supporting stock, and non-slipping stock-engaging 35 means for stretching the stock by repeated operations applied locally to an area lying within and not including its edges.

3. A machine of the class described having, in combination, means for supporting stock, continuously operating devices arranged to engage the stock at adjacent 40 points located wholly within and remote from the edge of the stock, then move apart to stretch it while remaining in contact 45 therewith at the points of initial engagement, then release the stock, and then move together again to reengage the stock, and actuating means for said devices.

4. A machine of the class described having, in combination, means constructed and arranged to engage stock at adjacent points, and actuating mechanism to cause said 50 means to move relatively apart to stretch the stock, to feed the stock, to release the stock, and to move reversely into position 55 for engaging an adjacent portion of the stock to be stretched.

5. A machine of the class described having, in combination, means constructed and 60 arranged to engage stock at adjacent points, and mechanism to move the engaging means laterally apart to stretch the stock progressively by repeated operations applied to successive portions of the stock, said mechanism being organized to cause the engaging 65

means to release the stock during a portion of the cycle of the machine to allow it to be fed or positioned independently of said engaging means.

6. A machine of the class described having, 70 in combination, means for seizing adjacent portions of stock lying within and not including its edge, and continuously operating mechanism to cause said means to stretch the stock by repeated operations 75 applied to successive portions of the stock and gradually producing therein over a local area a permanent fullness.

7. A machine of the class described having, 80 in combination, means for seizing adjacent portions of stock, and mechanism to cause said means to stretch the stock, to transfer the stock in the direction of feed, to release the stock, to move reversely and reengage the stock, and means to control the 85 extent of the feeding movements imparted to the stock.

8. A machine of the class described having, 90 in combination, means for seizing adjacent portions of stock, and continuously acting mechanism to cause said means to stretch the stock, to feed the stock, to release the stock, to move reversely and reengage the stock, and means to control the 95 direction in which the stock is fed.

9. A machine of the class described having, 100 in combination, means for successively effecting local stretching of the interior portions of stock by repeated operations, means for feeding the stock between the successive stretching operations, and means to control the direction in which the stock is fed.

10. A machine of the class described having, 105 in combination, means for successively effecting local stretching of the interior portions only of stock, means for feeding the stock between the successive stretching operations, and means to control the extent of the feeding movements.

11. A machine of the class described having, 110 in combination, means for successively effecting local stretching of the interior portions of stock, means for feeding the stock between the successive stretching operations, and means to control the direction and extent of the feeding movements.

12. A machine of the class described having, 115 in combination, means for successively seizing and stretching the interior portions of stock, means for feeding the stock between the successive stretching operations, and means to control the time at which the stretching means surrenders the stock to the feeding means.

13. A machine of the class described having, 120 in combination, continuously operating means for seizing stock at adjacent points and for moving the seizing means relatively apart to stretch the stock, means to feed the stock between successive stretching opera- 125

tions, and means to control the time at which the stretching means surrenders the stock to the feeding means.

14. In a machine of the class described, 5 the combination with pincers arranged to seize adjacent portions of stock and each having a fixed and a movable jaw, of yielding means for forcing the movable jaws toward the fixed jaws, and means for alternately effecting relative movements of the pincers toward and from each other to stretch successive portions of the stock.

15. In a machine of the class described, the combination with pincers arranged to 15 seize adjacent portions of stock and each having a fixed and a movable jaw, of yielding means for forcing the movable jaws toward the fixed jaws, means to vary the force of said yielding means for either pincer, 20 and means for alternately effecting relative movements of the pincers toward and from each other to stretch successive portions of the stock.

16. In a machine of the class described, 25 the combination with pincers arranged to seize adjacent portions of stock and each having a fixed and a movable jaw, of a spring for forcing each movable jaw toward its coöperating fixed jaw, means for causing 30 the pincers to feed the stock, including means to control the direction and extent of the feeding movements imparted to the stock, and means for alternately moving the pincers toward and from each other to suc- 35 cessively stretch and feed the stock.

17. In a machine of the class described, the combination with pincers having movable and fixed jaws arranged to seize adjacent portions of stock, of parallel links sus- 40 taining a movable jaw of each pincer in co- operative relation with a fixed jaw, yielding means for actuating the movable jaws and means for alternately effecting relative movements of the pincers in opposite direc- 45 tions to stretch the stock.

18. In a machine of the class described, the combination with upper holding means and a pincer arranged to engage adjacent portions of stock, said pincer having mov- 50 able and fixed jaws, of inclined parallel links sustaining the movable jaws of the pincer, yielding means to cause gripping engagement of the jaws with the stock, and means for causing movements of the pincer to suc- 55 cessively seize, stretch, release and reengage the stock.

19. In a machine of the class described, the combination with pincers having movable and fixed jaws arranged to engage ad- 60 jacent portions of stock, of oppositely inclined parallel links sustaining the movable jaws from the pincers, springs acting to force the movable jaws toward the fixed jaws, and means for causing simultaneous 65 reciprocating movements of the pincers in

opposite directions to successively seize, stretch, release, feed and reengage the stock.

20. In a machine of the class described, the combination with pincers having fixed jaws, of coöperating movable jaws and op- 70 positely inclined links sustaining said movable jaws from the pincers, guiding means extending from a sustaining link of each movable jaw, a rod movable in said guiding means, collars on said rod, stops on the rod 75 for engagement by the said guiding means to release the grip of the jaws on the work, an arm extending between said collars, and manually-controllable means for effecting 80 movements of the arm and the rod to position the stops for causing one stop to release one pincer before the other pincer is released.

21. In a machine of the class described, the combination with pincers having fixed 85 jaws, of coöperating movable jaws and means for sustaining said jaws from the pincers including oppositely inclined links having handled extensions by which the jaws may be lifted to release the work, per- 90 forated bosses in said extensions, a rod guided in the perforations, spaced collars on said rod, springs confined between said bosses and collars and normally acting to produce depression of the jaws to grip the 95 work, and stops arranged on the rod to be engaged by said extensions to lift the jaws automatically.

22. In a machine of the class described, 100 the combination with pincers having fixed jaws, of coöperating movable jaws and means for sustaining said jaws from the pincers including oppositely inclined links having handled extensions by which the jaws may be lifted to release the work, per- 105 forated bosses in said extensions, a rod guided in the perforations, spaced collars on said rod, springs confined between said bosses and collars and normally acting to produce depression of the jaws to grip the 110 work, stops arranged on the rod to be en- gaged by said extensions to lift the jaws au- 115 tomatically, and means for adjusting the rod to position one stop to release a pincer before the other pincer is released, said means comprising a crank arm located be- 120 tween said collars, a knee lever, and connec- tions between said arm and lever.

23. In a machine of the class described, 120 the combination with a work table having an opening therein, of pincers comprising arms embracing the table and coöperating grip- 125 ping jaws carried by the arms and arranged over said opening, and means for imparting repeated movements to the pincers in oppo- site directions to effect successive stretching of a predetermined area of the interior por- tions of stock.

24. In a machine of the class described, 130 the combination with a work table having

- an opening therein, of pincers comprising arms embracing the table and coöperating relatively fixed and movable gripping jaws carried by said arms and arranged over said opening, and means for imparting repeated movements to the pincers in opposite directions to stretch successive portions of the stock and to feed the stock between the stretching operations.
- 10 25. In a machine of the class described, the combination with a work table having an opening therein, of pincers comprising arms embracing the table and coöperating gripping jaws carried by the arms and arranged over said opening, means for guiding the pincers, and means for reciprocating the pincers comprising links connecting adjacent portions of said pincers, a bar connected with said links and having a cam slot, and 15 a power-driven shaft provided with a crankpin to enter said slot.
- 20 26. In a machine of the class described, the combination with two pincers arranged to engage stock at adjacent points, and means to move them relatively to stretch the stock progressively by repeated operations applied to successive portions of the stock, said operating means being constructed and arranged to impart a quick initial movement to a pincer followed by a slow pulling movement during which the stock is held under tension and then automatically to release a pincer.
- 25 30 27. In a machine of the class described, the combination with two pincers arranged to engage stock at adjacent points, and means to move them relatively to stretch the stock progressively by repeated operations applied to successive portions of the stock, said operating means comprising a sliding bar, toggle links connected to the pincers, a crank, and a cam slot in the bar located to receive the crank and formed to accelerate the initial movement of the pincers during 35 which the stock is being seized and to retard a later movement of the pincers during which they are stretching the stock.
- 40 45 50 55 60 65 28. In a machine of the class described, means for supporting and stretching interior portions of shoe upper stock comprising two pincers having lower jaws and upper jaws, links supporting the upper jaws and inclined downwardly and rearwardly relatively to the lower jaws whereby the jaws automatically grip and then pull the stock as the pincers are moved relatively apart and slide over it as they are moved relatively toward each other, and means for imparting to the pincers a quick initial movement apart to effect seizing of the stock and then a relatively slow continued movement apart to produce gradual stretching of the stock.
29. A machine of the class described having, in combination, means for supporting stock, continuously operating devices acting to engage the stock at adjacent points, then move apart to stretch it, then release the stock, and then move together again to re-engage the stock, and actuating means for 70 said devices constructed and arranged to impart a quick stock seizing movement, a long slow pull and a final quick return to starting position.
30. A machine for stretching uppers having, in combination, two adjacent similar pincers arranged to engage an upper in the same manner interiorly of and not including its edge and means for relatively moving said pincers apart to effect stretching of the 75 portion of upper located between them.
31. A machine for stretching uppers having, in combination, two adjacent pincers arranged to fixedly engage an upper interiorly of and not including its edge and 80 means for relatively moving said pincers apart in the same plane to effect stretching of the portion of upper located between them.
32. A machine for stretching uppers having, in combination, means for engaging an upper interiorly of and not including its edge and holding it, a pincer arranged to engage the upper also interiorly of and at 85 points removed from its edge and adjacent to the holding means, and operating mechanism to cause said pincer and holding means to grip the upper and retain it against slipping and then the pincer to move away from the holding means to stretch a portion of 90 upper located between said means and pincer and remote from the edge of the upper.
33. A machine for stretching uppers having, in combination, a work table, two pincers each comprising an upper and a 95 lower carrying arm located respectively above and below the table with clearance between the table and the upper arm for reception and movement of the work outspread on the table, jaws on the lower arms 100 projecting upwardly through the table, co-operating jaws on the upper arms disconnected from the lower jaws and movable relatively thereto to seize and release the interior portions of the work outspread on the 105 table, and means for moving the pincers apart to stretch the portion of the upper located between them.
34. A machine for stretching uppers having, in combination, two movable pincers 110 each comprising jaws and respective jaw carriers extending outside the jaws in the direction of movement at opposite sides of the pincers formed and arranged with clearance for a substantial distance from the 115 jaws to adapt the jaws to seize interior portions of the stock remote from and not including the edge of the work, the jaws of one pincer being located adjacent to the jaws of the other pincer, and means for op- 120

erating the jaws to stretch interior portions of the stock located between the pincers.

35. A machine for stretching uppers having, in combination, a work table, means arranged relatively thereto to seize at points remote from the edge and hold an interior portion of sheet stock supported on the table and not including the edge of the stock, and means for engaging an adjacent 10 interior portion of the stock and stretching the stock lying between said two means to produce a permanent fullness over the areas operated upon so as to permanently change its condition as compared with the portions 15 of the stock which are not stretched.

36. A machine for stretching uppers having, in combination, two adjacent pincers adapted to engage the stock and operating means to cause said pincers to stretch the 20 stock between the areas of initial engagement while the portions beyond said area remain substantially unaffected by such stretching action.

37. A machine for stretching uppers having, in combination, two adjacent pincers and operating means for causing them to non-slippingly engage interior portions of the stock not including its edge and stretch the portion of stock between them and 30 repeat their operation indefinitely.

38. A machine for stretching uppers having, in combination, upper holding means, a pincer adjacent thereto, said parts being arranged to permit the holding means and 35 pincer to engage interior portions of the stock located remote from and not extending to the edge of the stock, and operating means for causing the pincer to seize a portion of stock adjacent to the holding means 49 and retain it against slipping, stretch the stock between it and the holding means, release and reengage the stock and repeat its operations indefinitely to stretch the stock progressively.

45. 39. A machine for stretching uppers having, in combination, upper holding means, a pincer adjacent thereto, said parts being arranged to permit the holding means and pincer to engage interior portions of the 50 stock, and operating means for causing the pincer to seize a portion of stock adjacent to the holding means, stretch the stock between it and the holding means, release and reengage the stock and repeat its operations 55 indefinitely, said holding means and pincer being constructed and arranged to permit relative movement between the pincer and the upper on the one hand and the holding means on the other hand whereby successive 60 stretching actions may be made to take effect on different portions of the stock.

40. A machine for stretching uppers having, in combination, upper holding means, a pincer adjacent thereto, said parts being arranged 65 to permit the holding means and

pincer to engage interior portions of the stock, and operating means for causing the pincer to seize a portion of stock adjacent to the holding means, stretch the stock between it and the holding means, release and reengage 70 the stock and repeat its operations indefinitely, said operating means being constructed and arranged to cause the holding means and pincers to release the stock at different times to cause it to be repositioned 75 whereby successive stretching actions may be made to take effect on different portions of the stock.

41. A machine for stretching uppers having, in combination, upper holding means 80 and an automatically operating pincer constructed and arranged to engage an interior portion of the upper adjacent to the upper holding means, stretch the portion of upper between it and said means, feed the upper 85 relatively to the holding means, release the upper and reengage the fed stock in position to stretch a fresh portion located between it and the holding means.

42. A machine of the class described having, in combination, means for supporting stock, continuously operating means for applying local stretching to an interior portion of the stock not including its edge by repeated operations of the machine, and 95 means for producing feeding movement of the stock.

43. A machine of the class described having, in combination, means for supporting stock, and means for alternately stretching 100 and feeding the stock by repeated operations applied locally to an area lying within its edges, said supporting means and stretching means being constructed and arranged to permit the stock to be moved to change the 105 direction of the stretching action relative to the length or breadth of the stock during uninterrupted operation of the machine.

44. A machine of the class described having, in combination, means for supporting 110 stock, and means for stretching the stock by repeated operations applied locally to an area lying within and not including its edges, said stretching means being constructed and arranged to cause the stock to 115 be moved to cover the different portions of such area during different cycles of the machine.

45. A machine of the class described having, in combination, means for supporting 120 stock, continuously operating means for applying local stretching to an interior portion of the stock by repeated operations of the machine, and means by which feeding movement of the stock can be produced 125 forth and back through the stretching means.

46. A machine of the class described having, in combination, means for supporting stock, continuously operating means for ap- 130

- plying local stretching to an interior portion of the stock by repeated operations of the machine, and means for producing feeding movement of the stock, said supporting, stretching and feeding means being constructed and arranged to permit the direction of the advance of the stock to be modified while the machine is in operation.
47. A machine of the class described having, in combination, means for supporting stock, continuously operating means for applying local stretching to an interior portion of the stock by repeated operations of the machine, and means for producing feeding movement of the stock, said machine including means under control of the operator while the machine is running for varying the length of the feeding movements.
48. A machine of the class described having, in combination, means for supporting stock, and continuously operating means for applying local stretching to an interior portion of the stock not including its edge by repeated operations of the machine, said machine including means under control of the operator for varying the extent of the stretching action produced by successive cycles of the machine.
49. A machine of the class described having, in combination, means constructed and arranged to engage stock at adjacent points, and automatically repeating mechanism to cause said means to stretch and shift the stock progressively by repeated operations applied to successive portions of the stock, said engaging means and operating mechanism being constructed and arranged to permit the direction in which the stock is shifted to be varied.
50. In a machine of the class described, the combination with two pincers arranged to engage stock at adjacent points and means to move them relatively to stretch the stock progressively by repeated operations applied to successive portions of the stock, of means for manually opening both pincers together for the insertion of the stock.
51. In a machine of the class described, the combination with two pincers arranged to engage stock at adjacent points and means to move them relatively to stretch the stock progressively by repeated operations applied to successive portions of the stock, of variable means for automatically opening the pincers at different times.
52. In a machine of the class described, the combination with two pincers arranged to engage stock at adjacent points, means for moving the pincers in opposite directions to stretch the portion of stock located between them, and means for automatically opening one pincer before the other pincer is opened whereby said other pincer is caused to feed the stock during the last

part of its movement away from the first 65 pincer.

53. In a machine of the class described, the combination with two pincers arranged to engage stock at adjacent points, means for moving the pincers in opposite directions to stretch the portion of stock located between them, and means for automatically opening the pincers preparatory to their return movement, said means being adjustable to vary the length of the stretching movement.

54. In a machine of the class described, the combination with two pincers arranged to engage stock at adjacent points, means for moving the pincers in opposite directions to stretch the portion of stock located between them, and means for automatically opening the pincers preparatory to their return movement, said means being adjustable to cause either pincer to open first and 85 the other to feed the stock before it is opened.

55. In a machine of the class described, the combination with two pincers arranged to engage stock at adjacent points, means for moving the pincers in opposite directions to stretch the portion of stock located between them, and means for automatically causing one pincer to cease pulling while the other pincer continues to pull the stock 95 whereby the stock is advanced with the latter pincer.

56. In a machine of the class described, means for supporting and stretching interior portions of shoe upper stock comprising 100 two pincers having lower jaws, and upper jaws, links supporting the upper jaws and inclined downwardly and rearwardly relatively to the lower jaws whereby the jaws automatically grip and then pull the stock 105 as the pincers are moved relatively apart and slide over it as they are moved relatively toward each other, and means for relatively moving the pincers.

57. In a machine of the class described, 110 means for supporting and stretching interior portions of shoe upper stock comprising two pincers having lower jaws, and upper jaws, links supporting the upper jaws and inclined downwardly and rearwardly 115 relatively to the lower jaws, mechanism for moving the pincers simultaneously in opposite directions to stretch the upper, and means by which the upper jaws of the two pincers may be simultaneously lifted manually to permit manipulation of the upper within the pincers.

58. In a machine of the class described, 125 means for supporting and stretching interior portions of shoe upper stock comprising two pincers having lower jaws, and upper jaws, links supporting the upper jaws and inclined downwardly and rearwardly rela-

tively to the lower jaws, mechanism for moving the pincers simultaneously in opposite directions to stretch the upper, and extensions on two links of the upper jaws 5 of the pincers to form levers which can be pressed together to lift the upper jaws.

59. A machine of the class described having, in combination, means for supporting stock, and means acting in a direction substantially parallel with the plane of the stock on the supporting means and upon a limited area of the stock to permanently stretch and produce a fullness over said area as compared with surrounding portions of 15 the stock.

60. A machine of the class described having, in combination, means for supporting stock, and continuously operating means for applying local stretching to an interior portion of the stock not including its edge sufficient to appreciably alter its condition as compared with its edge portions so that the stretched portions of the stock will fit a curved surface of a last. 20

61. A machine of the class described having, in combination, means for supporting stock, and means for so stretching the stock by repeated operations applied to an area lying wholly within but not including its 25

edges as to permanently change the condition of the stretched portions to cause the stock to fit variations in contour of an irregularly shaped form. 30

62. In a stretching machine, members relatively movable toward and from one another and engaging material to be operated upon and movable apart to stretch it more over its interior portion than at its edges and thereby produce a fullness at said interior portion, and means for effecting successive relative movements of the engaging means. 35

63. A machine of the class described having, in combination, spaced pairs of pincer jaws for engaging the opposite sides of stock, and continuously operating means moving in a plane transversely of the plane of the stock to cause said jaws to seize the stock, to move apart to stretch it, and to move reversely to release the stock. 40 45

In testimony whereof we have signed our names to this specification in the presence of two subscribing witnesses.

ARTHUR L. RUSSELL.
CHARLES E. GRUSH.

Witnesses:

CHESTER E. ROGERS.

Copies of this patent may be obtained for five cents each, by addressing the "Commissioner of Patents, Washington, D. C."

It is hereby certified that in Letters Patent No. 1,313,917, granted August 26, 1919, upon the application of Arthur L. Russell, of Boston, and Charles E. Grush, of Beverly, Massachusetts, for an improvement in "Stretching-Machines," errors appear in the printed specification requiring correction as follows: Page 7, lines 5 and 6, claim 35, strike out the words "at points remote from the edge"; same page, line 18, claim 36, after the word "stock" insert the words *at points remote from the edge*; same page and claim, line 21, for the word "area" read *areas*; and that the said Letters Patent should be read with these corrections therein that the same may conform to the record of the case in the Patent Office.

Signed and sealed this 30th day of December, A. D., 1919.

[SEAL.]

M. H. COULSTON,

Acting Commissioner of Patents.

Cl. 12—51.
